UNITED STATES PATENT OFFICE.

GEORGE S. COX, OF FITZWATERTOWN, PENNSYLVANIA, ASSIGNOR TO HIMSELF, AND WALTER S. COX, OF PHILADELPHIA, PENNSYLVANIA, TRADING AS GEORGE S. COX AND BROTHER.

HEAD-MOTION FOR LOOMS.

SPECIFICATION forming part of Letters Patent No. 795,251, dated July 18, 1905.

Original application filed December 31, 1903, Serial No. 187,266. Divided and this application filed March 16, 1904. Serial No. 198,384.

To all whom it may concern:

Be it known that I, GEORGE S. Cox, a citizen of the United States, residing at Fitzwater-town, county of Montgomery and State of Pennsylvania, have invented a new and useful Improvement in Head-Motions for Looms, of which the following is a full, clear, and exact description, reference being had to the accompanying drawings, which form a part of this specification.

The object of my invention is to provide a head-motion for looms by means of which any device on the loom may be caused to operate intermittently and momentarily.

This application is a division of an application filed by me December 31, 1903, Serial No. 187,266, for an improvement in looms, wherein the invention forming the subject-matter of this application is described and shown as adapted to actuate mechanism for moving a yarn-carrier and a hair-selector alternately into operative relation with a nipper adapted to grasp the yarn or hair presented to it and pull it across the loom, whereby a cloth is formed having alternate sections of linen and hair weft. The invention forming the subject-matter of this application is not, however, limited to the actuation of such or any weft-changing mechanism, but may be utilized for the purpose of operating any devices on the loom which it is desired to occasionally throw into action at predetermined times, and therefore the description and drawings of this application are confined to the novel mechanism embodying my invention and the mechanism immediately associated therewith.

The invention consists of the general or specific construction and arrangement of devices hereinafter described and claimed.

In the drawings, Figure 1 is a plan view of the shedding-motion and pattern mechanism for actuating the same, including my novel head-motion. Fig. 2 is a section on the line 2 2 of Fig. 1. Fig. 3 is a front elevation of the same; and Fig. 4 is a detail view, in side elevation, of the pattern-drum, its shaft, and the gears and wheels carried thereby.

a is the frame of the shedding-motion.

b is the usual oscillating shaft, having secured thereto the usual double-ended levers *c c*.

d d, &c., are the usual notched draw-bars of an ordinary shedding-motion, *e* the knife for actuating the draw-bars, and *e'* the sliding rack, said knife and rack being connected, respectively, by connecting-rods *f f'* with the opposite ends, respectively, of the double-ended levers *c c*.

g is a flexible connection, the upper end of which is secured to the end of a lever *h*, pivoted on the frame. The lower end of the flexible connection *g* may be secured to any mechanism which it is desired to operate. The lever *h* is also connected by a wire *h'* with one end of a draw-bar *i*.

j is a spring, one end of which is secured to the lever *h*, while the other end is secured to the frame. This spring normally holds the lever *h*, flexible connection *g*, and draw-bar *i* in their normally inoperative positions.

The draw-bar *i* is made in two sections hinged together at *i'*. The other end of the draw-bar is notched and adapted to be engaged by the constantly-reciprocating knife *e*. Normally, however, the knife *e* is ineffective to actuate the draw-bar *i*, the notched end of the draw-bar being held above the path of travel of the knife *e* by means of one end of a pivoted lever *k*, the other end of lever *k* resting on a support *k'* in such a manner that the boss *k'* on lever *k* just clears the pattern-chain *l*. When one of the lugs *l'* of the pattern-chain travels under the boss *k'* and lifts the corresponding end of the lever *k*, the notched end of the draw-bar *i* drops. Then the knife *e* actuates the draw-bar *i*, thereby actuating the flexible connection *g*. As the knife *e* recedes the spring *j* returns the draw-bar *i* to its normal position.

The following mechanism is provided to actuate the pattern-chain: *m* is a sprocket-wheel loose on the pattern-drum shaft *r'* and around which the pattern-chain extends. Also loose on the shaft *r'* and secured to the sprocket-

wheel m is a toothed wheel n . o is a disk secured to the shaft o' , said disk having a single tooth which at each rotation of the disk engages the toothed wheel n and moves it and the sprocket-wheel m a distance of one tooth. The shaft o' has also secured to it a gear p , meshing with a gear q on the pattern-drum shaft r' . The shaft r' , besides carrying the pattern-drum r , has secured to it a ratchet-wheel s , which is actuated by a two-part pawl-lever s' , pivoted to an arm b' , secured to shaft b . At each oscillation of shaft b , therefore, the pawl-lever s' actuates the ratchet-wheel s , which, through shaft r' , gear q , gear p , and shaft o' , turns the toothed disk o , and the disk o after the number of turns required to completely rotate it actuates the toothed wheel n , sprocket-wheel m , and pattern-chain k . Inasmuch as the pattern-chain is moved but once in a number of reciprocations of the knife e , the lug l' on the pattern-chain would continue to hold up the lever k , and the draw-bar i would be reciprocated at each oscillation of the shaft b during the complete revolution of the disk o , whereas the object is to cause said draw-bar and the mechanism actuated thereby to operate only once when a lug on the pattern-chain passes under the lever k . Means are therefore provided to move the pattern-chain lug from under the lever k immediately after the knife e has actuated the draw-bar. This is accomplished by means of a bar t , pivoted to a crank u on the oscillating shaft b , whereby the bar is constantly reciprocated. The bar is provided with a shouldered lateral projection t' , which on its movement from left to right, as shown in the drawings, strikes the lug l' and moves it from under the lever k , thereby permitting lever k to drop and lift the draw-bar i out of the path of travel of the knife e .

To prevent the projection t' of the bar t from moving the pattern-chain lug until the latter reaches the exact position necessary for it to assume to lift the lever k , I make the rear face t^2 of the projection t' inclined, so that when it strikes the lug the latter will force the bar t laterally out, just as it completes its stroke, against the tension of the spring v , to which the free end of bar t is secured. In the reciprocations of the bar t the lug t' is not carried far enough toward the left to permit the shouldered part of the lug t' to pass behind the lug l' until said lug l' has been moved into a position to lift the lever k to permit the draw-bar d to drop. Therefore during a number of reciprocations of said bar t while the lug l' is close to the point where it is enabled to lift the lever k the inclined portion t^2 of the bar t strikes said lug and is forced laterally outward; but, as above stated, when said lug l' is at this point said part t is not carried far enough to clear the lug l' ; but after the lug l' has been moved into a position to lift the lever k to permit

the draw-bar to drop the knife e moves from left to right, shifting the draw-bar, and the simultaneous movement of the bar t toward the left is sufficiently far not only to cause the inclined portion t^2 of the bar t to strike the lug l' and be moved laterally outward, but also to cause the projection t' to entirely clear the lug l' , permitting the shouldered part of the lug t' to pass behind the lug l' , whereupon the spring v draws the bar t into its normal position, causing the projection t' to drop back of the lug and, as before described, move it out of operative position during the travel of the bar t from left to right.

Having now fully described my invention, what I claim, and desire to protect by Letters Patent, is—

1. In a loom, in combination, a draw-bar, a constantly-reciprocating knife adapted to actuate said draw-bar, pattern mechanism including a lug adapted to control the movement of said draw-bar into and out of the line of travel of said knife, driving means whereby said pattern mechanism is driven intermittently, and a device, independent of the normal pattern-mechanism-driving means, adapted to move said lug out of operative position after said knife actuates said draw-bar, substantially as described.

2. In a loom, in combination, a draw-bar, a constantly-reciprocating knife adapted to actuate said draw-bar, pattern mechanism including a lug adapted to control the movement of said draw-bar into and out of operative position, means for advancing said lug once in a plurality of reciprocations of the knife, and a device independent of such means adapted to render said lug inoperative after a single actuation of said draw-bar, substantially as described.

3. In a loom, in combination, a draw-bar, a constantly-reciprocating knife adapted to actuate said draw-bar, pattern mechanism including a lug adapted to control the movement of said draw-bar into and out of the line of travel of said knife, pattern-mechanism-actuating means for advancing said lug once in a plurality of reciprocations of the knife, a device independent of such means adapted to render said lug inoperative after a single actuation of said draw-bar, and means rendering said device normally inoperative.

4. In a loom, in combination, a draw-bar, a constantly-reciprocating knife adapted to actuate said draw-bar, a lever adapted to control the movement of said draw-bar into and out of operative position, a pattern-chain, a lug thereon adapted to lift said lever, driving means whereby said chain is driven intermittently, and a device independent of the pattern-chain-driving means adapted to engage said lug and move it away from said lever after said knife reciprocates said draw-bar, substantially as described.

5. In a loom, in combination, a draw-bar, a constantly-reciprocating knife adapted to actuate said draw-bar, a lever adapted to control the movement of said draw-bar into and out of operative position, a pattern-chain, a lug thereon adapted to lift said lever, driving means whereby said chain is driven intermittently, a reciprocating bar, and a projection on said bar adapted to engage said lug and move it away from said lever after said knife reciprocates said draw-bar, substantially as described.

6. In a loom, in combination, a draw-bar, a constantly-reciprocating knife adapted to actuate said draw-bar, a lever adapted to control the movement of said draw-bar into and out of operative position, a pattern-chain, a lug thereon adapted to lift said lever, driving means whereby said chain is driven intermittently, a reciprocating bar, and a projection thereon having an inclined face adapted to strike said lug, in the movement of the bar in one direction and thus move the bar laterally, and a spring adapted to return said bar to its normal position, thereby bringing said projection into position to move said lug away from said lever in the return movement of the bar, substantially as described.

7. In a loom, in combination, a draw-bar, a constantly-reciprocating knife adapted to actuate said draw-bar, a pattern-chain, a lug thereon adapted to control the movement of said draw-bar into and out of the line of travel of said knife, an oscillating shaft, connections therefrom to the knife whereby the latter is reciprocated, a pattern-shaft, a ratchet on the pattern-shaft, a pawl engaging said ratchet and actuated from the oscillating shaft, a gear on said pattern-shaft, a counter-shaft, a gear thereon driven by the first-named gear, a disk on said counter-shaft having a tooth, a toothed wheel loose on the pattern-shaft and driven intermittently by said disk, and a sprocket-wheel loose on the pattern-shaft and driven by said toothed wheel and around which said pattern-chain extends, substantially as described.

8. In a loom, in combination, a draw-bar, a constantly-reciprocating knife adapted to actuate said draw-bar, a lever adapted to control the movement of said draw-bar into and out of

operative position, a pattern-chain, a lug thereon adapted to lift said lever, driving means whereby said chain is driven intermittently, a reciprocating bar, and a projection thereon having an inclined face adapted to strike said lug, in the movement of the bar in one direction and thus move the bar in one direction and thus move the bar laterally, and a spring adapted to return said bar to its normal position, thereby bringing said projection into position to move said lug away from said lever in the return movement of the bar, a reciprocating bar, and a projection on said bar adapted to engage said lug and move it out of operative position after said knife actuates said draw-bar, substantially as described.

9. In a loom, in combination, a draw-bar, a knife adapted to actuate said draw-bar, a lever adapted to control the movement of said draw-bar into and out of operative position, a pattern-chain, a lug thereon adapted to lift said lever, an oscillating shaft, connections therefrom to the knife whereby the latter is reciprocated, a pattern-shaft, a pattern-drum thereon, a ratchet on the pattern-shaft, a pawl engaging said ratchet and actuated from the oscillating shaft, a gear on said pattern-shaft, a counter-shaft, a gear thereon driven by the first-named gear, a disk on said counter-shaft having a tooth, a toothed wheel loose on the pattern-drum shaft and driven intermittently by said disk, and a sprocket-wheel secured to said toothed wheel and around which said pattern-chain extends, a reciprocating bar, a projection thereon having an inclined face adapted to strike said lug in the movement of the bar in one direction and thus move the bar laterally, and a spring adapted to return said bar to its normal position, thereby bringing said projection into position to move said lug away from said lever in the return movement of the bar, substantially as described.

In testimony of which invention I have hereunto set my hand, at Philadelphia, on this 11th day of March, 1904.
